A. BOYNTON

COMBINATION WASHING TOOL AND SWAB

Filed Feb. 5, 1924

UNITED STATES PATENT OFFICE.

ALEXANDER BOYNTON, OF SAN ANTONIO, TEXAS.

COMBINATION WASHING TOOL AND SWAB.

Application filed February 5, 1924. Serial No. 690,792.

This invention relates to washing tools and swabs especially adapted for use in wells.

- An important object of this invention is to provide novel means whereby to clean the flow surface of a well of all mud, drill cuttings, and other matter which would be likely to retard the production of oil or water as the case may be.
- 10 A further object is to provide a washing tool which may be conveniently converted into a swab when desired and which on the withdrawal of the tool when functioning as a swab will lift fluid from the well and create a strong vacuum in the lower portion of the well so that any obstructions remaining after the washing operation will be dislodged.

20 A further object is to provide a combination washing tool and swab which is of highly simplified construction, durable in use and cheap to manufacture.

Other objects and advantages will be apparent during the course of the following 25 description.

In the accompanying drawings forming a part of this application, and in which like numerals are employed to designate like parts throughout the same,

30 Figure 1 is a central vertical section of the invention.

Figure 2 is a side elevation of the tool illustrated in Figure 1.

Figure 3 is a horizontal sectional view taken on the line 13—13 of Figure 1,

Figure 4 is a horizontal sectional view taken on line 14—14 of Figure 2,

Figure 5 is a perspective of one of the expansive rubbers or contact members embodied in the invention as illustrated in Figures 1 and 2,

Figure 6 is a side elevation illustrating a modified form of burr cutter,

Figure 7 is a detail view in side elevation 45 of the spring dart assembly.

Figures 1 to 5 illustrate an important one of a number of modifications to which the invention is susceptible, an outstanding principle being the highly developed combination feature that renders the tool instantly convertible from a washing tool to a swab and vice versa, and consists of a tubular body 150 having its intermediate portions

provided with outlet ports 151 for the discharge of liquid.

Figure 1 illustrates that a pair of yieldable rubbers or rings 152 are mounted on the tubular body at opposite ends of the series of openings or ports 151 and are adapted to have liquid tight contact with a perforated liner to clean the perforations of the liner and the flow surfaces of the well of mud, drill cuttings and other matter which would be likely to retard production.

In this form of the invention the outer and inner rubber ring end retaining cups 154 and 155 respectively have their inner surfaces flared and recessed for the reception of the tapering end portions 156 of the rubbers. It will be seen that the end portions of the 60 rubbers 156 are snugly received in the flared inner portions of the cups 154—155, and are consequently held against expansion when the liquid flows under pressure through the openings 157. During the washing operation the fluid is supplied under pressure 65 through the tubular body 150 and that fluid which passes through the openings 157 expands the intermediate portions of the rubbers 152 and consequently causing the same 70 to have liquid tight contact with the adjacent portions of the liner. By reason of this arrangement the liquid supplied to the openings 151 is forced to pass through the perforations in the liner and thoroughly wash 75 the flow surfaces of the well.

Attention is especially directed to the fact that the ends of yieldable sealing members 152 are prevented from coming into contact with the liner as the ends of the same are fully protected, nor can exposed edges of sealing members be forced into damaging contact with casing or liner because the rubber ring end retaining cups 154 and 155 prevent expansion at such points. Additional assurance may be had in this respect by imbedding the wires 75 in the corners of the 80 rubbers.

By positioning the tapered ends 156 of the rubbers or sealing members 152 in the 85 cupped ends of the retainers 154 and 155, leaking is positively prevented whether the tool is used either for washing purposes or as a swab.

The tool when positioned as illustrated in 90 Figures 1 and 3 is adapted for use in wash-

ing the perforations of the liner and the flow surfaces of the well; and when the parts are positioned as illustrated in Figures 2 and 4, the tool functions as a swab.

- 5 A sleeve 160 is mounted on the main body between the inner retainers 155 and is provided with openings 161 adapted to register with the openings 151 to permit of the discharge of the fluid when functioning as a 10 washing tool. To convert from swab to washing tool, one of the rubber retainers 155 may be slightly rotated so that it is free from locking engagement with the sleeve, and the sleeve is then turned to the desired 15 position with openings 151 and 161 in registration. When the sleeve has been thus positioned the retainer 155 is again returned to locking engagement with the sleeve so as to hold the sleeve against accidental turning. 20 In practical operation, however, the sleeve 160 is rotated by a pipe wrench without the necessity of freeing the locking engagement.

When the shoes 25 are applied to the body 5, or the sleeve 160 rotated so as to close 25 holes 161, the tool may be used as a plunger pump in an ordinary casing or working barrel. As a pump it has great advantages over the ordinary pump because the rubber rings 30 are completely efficient until they wear out, whereas cups begin to lose their efficiency from the beginning.

This washing tool may be effectively used 35 to accurately locate holes, splits, or openings in casing. By lowering the tool into the well with pump pressure applied the expandable rubber rings 152, Fig. 1, will seal off against the casing, and the pump will remain stalled until the washing tool reaches the hole or 40 split in casing whereupon the pump will immediately begin to work, thus establishing circulation through the hole or split, and thus locate exactly the hole or opening that may need repair.

45 The lower portions of the body 150 may be provided with upper and lower spiral burr cutters 170—171 oppositely directed so that the turning effect when a burr is encountered is neutralized. In other words 50 when a burr is engaged by the cutters 170 the tendency of the coupling member 172 to turn is reduced to a minimum, thus preventing the joints of the tool or wash pipe from becoming unscrewed while being raised or 55 lowered in the well.

In this form of the invention, the usual dart 175 is provided and a spring 180 may be employed to normally hold the same in its unseated position when the tool is used as a 60 swab. The spring 180 is preferably of the type and form shown in the drawings (see Figs. 1 and 7), and has its large lower end seated against a shoulder 181 and its small upper end engaged with the head 182 of a 65 bolt 183 secured to the upper end of the dart

175 and upstanding therefrom. Whenever the swab has been let too far down and under more fluid than the swabbing line can lift, the operator can back the swab down the well until the pressure on the lower side of 70 the dart valve is approximately equal to the pressure on the upper side of the dart valve. The spring then releases the dart, and the swab may again be slowly raised at a speed that will not seat the dart, thus allowing 75 the swab to unload through the dart seat until a point is reached where the load can be lifted; more speed is then applied to the swabbing line and the quickened motion of the swab immediately seats the dart, the 80 interia of the dart valve overcoming the tension of the spring, whereupon the swab is withdrawn with its proper load. This automatic unloading device is one of the novel and essential features of this invention. In 85 converting this tool from a swab to a washing tool, it is not necessary to remove the spring beneath the dart because when functioning as a washing tool, the same internally applied force that expands the rubber rings 90 152, Fig. 1, compresses the spring and seats the dart.

Water or slush may be removed from beneath the oil in the well by screwing on 95 one or more joints of pipe above the swab, fastening bailing line to the top of same with ordinary open bailer top, removing dart bottom or bottom valve, thus leaving the pipe open through the swab, or bailer 100 as now converted, and lowering same down below the oil and into the water or slush and withdrawing same from the well. The water or slush thus becomes entrapped between the swab and the open top and is brought out while the oil above the top escapes downward through the open pipe. In 105 this manner mud or slush may be removed from a well without removing and wasting the oil which accumulates on top of the mud or slush during the period of bringing in 110 the well.

Figure 6 illustrates that during the lowering of the tool the burrs may be removed and substituted by an annular cutter 176 which may be mounted on the upper end 115 of the coupling member 177, corresponding to the part 172.

In operation, oil, water, or steam as the case may be is introduced into the tubular body 150 whence it passes through the perforations 151—161 and through the perforated liner at the lower end of the casing (not shown) so as to thoroughly clean the bottom of the well as will be fully herein-after pointed out. It will be seen that the tubular body 150 is provided inwardly of the 120 expandable members 152 with openings 157 by means of which the fluid under pressure 125 is permitted to force the rubber rings tightly 130 into engagement with the inner wall of the

liner (not shown) and thereby prevent the escape of the liquid past the rings. In other words the rings engage the liner at spaced points and thereby form an annular 5 chamber for the passage of the liquid.

The lower portion of the tubular body 150 is closed by a check valve or dart 18 carried by a bushing or valve casing 20, the said casing 20 being carried by the coupling 10 172 threaded onto the lower portion of the body 150.

In use the tool is lowered into the well on a drill stem or wash-pipe. When the washing tool has reached the perforated 15 liner, a circulating pump is started and the water or oil is forced out through the drill stem or wash pipe and into the tool. The force of the liquid is exerted upon the inner side of the rubber rings 152 so that the rubber 20 rings are expanded and tightly engaged with the wall of the liner. The water, oil, or other washing fluid is discharged from the tool under high pressure through the perforations and through the liner and in this 25 manner the wall is washed clean, for increasing the flow surface and clearing the same so that the tubing will not be fouled or the pumping mechanism will not be cut or damaged by inflow from the formation.

30 By circulating coarse sharp sand, emery, adamantine, or other hard, sharp cutting material, in the washing fluid, the walls of the well may be cut or reamed to almost any desired diameter, depending upon the 35 pump pressure, mixture of cutting compound and length of time applied. Herein lies one of the major advantages of the invention.

When the washing tool is withdrawn from the well, the expensive force exerted upon 40 the lower ring 152 causes the tool to act as a swab in a one string well. In other words, with the casing and liner of the same size the rings 152 will engage the casing so that as the tool is withdrawn the well is bailed 45 out to the top of the perforated liner.

In hard or honey-comb formations, this washing tool will wash and clean the pores of the honey-comb thus removing all mud and drill cuttings to permit the oil or water 50 to come more freely into the well.

In soft formations, it will, so to speak, ream the hole to many times its original diameter, thus washing out the mud and loose formations which would otherwise 55 come back against the liner and eventually work through the perforations of the liner and foul and damage the pumping mechanism. Reaming or enlarging the diameter of the well at the same time exposes more 60 producing area so that freer and larger flow is allowed to come into the well.

With this washing tool in use the action of the pump indicates the exact places of the liner which most need washing or cleaning. 65 When the pump is forcing washing fluid

down through the washing tool, the pump will labor when the washing tool is opposite closed or clogged perforations in the liner. In this manner, the operator will know the exact points at which the obstructions are 70 located. Great pressure in gas or oil bearing sands pushes the mud and soft formations against the liner, often completely sealing the perforations, thus making it impossible for the gas or oil to come into the well. 75 These are the places that need washing most, and the places which never get washed effectively, as wells are now washed. When such places in a liner are reached, the pump labors and indicates where the oil or gas 80 seeks to come in, but is choked off and held back by the mud or other soft formations. Special attention may be given to the clogged places in the well so that the well may be brought in properly or if an old 85 well, made to resume profitable production.

As a result of the practical use of this invention in wells, old oil wells have been made to resume profitable production by 90 washing with this tool after the perforations in the liner had been completely closed and production entirely shut off.

By washing with hot water, steam, crude oil, gasoline, coal-oil or other proper solvent, this washing tool will dislodge paraffine, 95 asphalt, tar or other sediment which obstructs or closes the perforations in the liners of old wells, and at the same time clean and ream the walls, removing mud originally left in the well, as well as to ream out soft formations that were not properly reamed, washed, or cleaned at the beginning.

By the use of this invention, wells which have ceased to flow or produce because of the liners becoming choked or clogged can 105 again be made to resume production, providing of course the oil sands have not been completely drained.

This washing tool also functions as a swab when it is being withdrawn from the well. 110 In one string wells having the same size casings as liner, this washing tool, while being withdrawn picks up all fluids above the perforations in the liner and lifts it out of the well, thus acting as a combination 115 washing tool and swab. Thus the well is not only washed but is bailed clean to the top of the liner. During the withdrawal of the tool, a vacuum is created beneath the tool, and this vacuum thus created aids the 120 oil or water to break through any remaining obstructions and come into the well.

Having thus described the invention, what is claimed is:—

1. A tool for use in wells comprising a 125 tubular body having water discharge openings, a sleeve receiving said body and having openings adapted to register with said first named openings, sealing members mounted on said body at opposite ends of said sleeve, 130

retainers mounted on said body and engaging said sealing members, said retainers being adapted to engage the ends of said sleeve to hold the sleeve in a set position with the openings of the same either in or out of registration with the openings in the tubular body.

2. A washing tool comprising a tubular body having fluid passages, expandible sealing members of annular formation mounted on said body and having tapered end portions, retaining members mounted on said body and having their inner portions flared and formed with sockets to snugly receive the tapered end portions of said sealing members, and a sleeve mounted on said body and engaged by the retaining members whereby the sleeve is held in a set position.

3. A combination washing tool and swab comprising a cylindrical body having a plurality of discharge openings, a sleeve fitted on the body and having a plurality of discharge openings adapted to be brought into registration with the discharge openings of the body or to be rotated out of registration therewith, an expandible sealing member encircling the body adjacent each end of the sleeve, and a collar threaded upon the body at a point between each end of the sleeve and its associated expandible sealing member, each collar being adapted for retaining the associated end of its respective sealing member upon the body member, and said collar cooperating for holding the sleeve against turning upon said body member.

ALEXANDER BOYNTON.
